THE NORRIS PETERS CO., PHOTO-LITHO., WASHINGTON, D. C.

UNITED STATES PATENT OFFICE.

JOHN A. MOSHER, OF CHICAGO, ILLINOIS, ASSIGNOR TO THE ADAMS & WESTLAKE COMPANY, OF SAME PLACE.

PHOTOGRAPHIC-ROLL HOLDER.

SPECIFICATION forming part of Letters Patent No. 665,691, dated January 8, 1901.

Application filed June 6, 1898. Serial No. 682,755. (No model.)

To all whom it may concern:

Be it known that I, JOHN A. MOSHER, a citizen of the United States, and a resident of Chicago, county of Cook, and State of Illinois, have invented certain new and useful Improvements in Roll-Holders, of which the following is a specification, and which are illustrated in the accompanying drawings, forming a part thereof, and in which—

10 Figure 1 is a rear elevation of the roll-holder, partly in section, with its back plate removed. Fig. 2 is a sectional view on the line 2 2 of Fig. 1. Fig. 3 is a plan view on the line 3 3 of Fig. 1. Fig. 4 is a detail front 15 elevation of the roll-holder when open. Fig. 5 is a sectional view on the line 5 5 of Fig. 1. Fig. 6 is a detail of a part of the roll-holder. Figs. 5 and 6 are drawn upon a larger scale than the remainder of the figures.

20 The invention relates to roll-holders for that class of hand-cameras in which the sensitized medium is inclosed within a light-proof case having a hinged cover and in which mechanism is provided for opening and 25 closing this cover from without the case.

The object of the invention is to provide an improved form of roll-holder particularly for use in connection with this type of camera, but having features also which may be 30 applied to various styles of instruments.

This invention consists in the peculiar form of roll-holder herein shown and described and possessing the various novel features of construction, as hereinafter set forth.

35 The camera-case A has an openable section B, which, as shown, is approximately one-half of the top side of the oblong rectangular case, being hinged at b to the remainder of this side of the case and being provided with 40 a suitable clasp for engagement with the rear end a of the case.

The roll-holder C is an oblong rectangular box, preferably made of metal, adapted to fit within the rearward end of a camera-case, being provided at its forward edge with lateral wings c, adapted to enter the vertical grooves or ways in the inner faces of the side walls of the case. The rearward side C' of the roll-holder is provided with a continuous 45 flange adapted to frictionally engage the body portion, and the front wall D of the roll-

holder, being the supporting-plate for the sensitized film, has at each end a vertical slot through which the film F passes, and immediately back of each of these slots is located 55 an antifriction-roller E E', over which the film is turned. The film F is placed within the roll-holder upon the spool G and is transferred to the spool H, also mounted within the roll-holder, by being passed over the outer 60 surface of the plate D.

The front of the roll-holder is provided with a cover J, hinged across its lower edge to the lower edge of the roll-holder, as indicated at j, and provided with a continuous flange J' 65 at its edges, turned inwardly toward the face of the roll-holder, the hinge-plate j being extended downwardly beyond the lower edge of the cover. The plate D is provided with a continuous groove d near its edges, adapted 70 to receive the flange J', so as to make therewith a light-tight joint. The upper edge of the plate D is turned forwardly and is provided with beaded portions, as shown at d', with which coöperate friction-clasps J³, 75 formed upon the upper end of a plate J², secured to the outer face of the cover J across its top edge, this plate being provided with a thumb-piece J⁵, by which it may be conveniently opened. The ends of the plate J² 80 project beyond the edge of the cover J, as shown at J⁴, so that when the roll-holder C is inserted within a camera-case, its wing-pieces c sliding within grooves or ways in the side walls, the projections J⁴ afford means for engaging with suitable opening mechanism of a camera.

The roll-holder is so constructed that the spools upon which the films now in general use are sold may be mounted within it. These 90 spools are usually provided with central end sockets to receive trunnions fixed within the roll-holder. Such a trunnion g is set in the top of the case C to engage the upper end of the spool G. Preferably a friction-plate g' is 95 fixed upon the trunnion g. The upper end of the spool H is engaged by a similar trunnion m, being the prolongation of a stud-shaft journaled in the top of the case C and carrying a ratchet-wheel M, with which coöperates 100 a pawl O, held to the ratchet-wheel by the spring o. Means are provided for positively

interlocking the ratchet-wheel and spool H, so that they will rotate together. As shown, this is accomplished by locating studs m' of any desired number on the disk face of the 5 wheel M, so that they will engage the end of the spool. The lower trunnion p for each spool is mounted upon a plate P, carried by a sleeve p' , mounted loosely upon a post Q, firmly set in the top and bottom of the case 10 C. A contracting-spring q is wound upon the upper end of each of the posts Q and secured at its upper end to the post and at its lower end to the sleeve p' , so that it draws the plate P upwardly. A stem P' projects 15 backwardly from each of the plates P and is held under a guide or retaining plate R, secured to the bottom of the case C and resisting the pull of the spring q . The plate R is provided with a recess r for each of the stems 20 P', so located that these stems enter them when the plates P are swung to such position that the trunnions p , carried by them, are in line with the trunnions g m , respectively. The recess r is of such depth that it allows 25 the plates P to bear with the full strength of the springs q upon the spools. The spools are readily inserted within the roll-holder by swinging the plates outwardly to the position shown by dotted lines in Fig. 3, placing the 30 spools upon them and turning them back into the case. As the stems P enter the recess r the plates P rise and bring the spools into engagement with the upper trunnions. The recess r serves the further purpose of 35 preventing accidental angular movement of the plates P. The upper end of the shaft m carries a turn-button M', by means of which the spool H may be rotated to transfer the film from the spool G. The ratchet and pawl 40 M O prevent the reverse motion of the spool H, and the friction of the spool G upon the spring-controlled plate P, supporting it, and the plate g' provides for the necessary tension of the film.

45 Any desired means for indicating the movement of the film may be employed. The most approved method of mounting films now in vogue is that in which there is employed a backing of opaque material interrolled upon 50 the spool with film, and upon this backing indicating characters for the several sections of the film are plainly marked. In order to expose these characters to the view of the operator, there is provided an observing-aperture in the plate J and another in the top of 55 the case C, as shown at S, and these are connected by a tube s, so that as the turn-button M' is rotated the character marking the next section of the film to be brought to the position of exposure may be readily seen.

I claim as my invention—

1. In a roll-holder, a case adapted to contain a pair of spools and having a plate D over which a film may be drawn for exposure, such

plate and one of the walls of the case perpendicular thereto each having an observing-aperture, opaque walls inclosing the line of vision from one of said apertures to the other, and a hinged cover for the plate D. 65

2. In a roll-holder, the combination with a 70 case, of a fixed trunnion mounted within the case for receiving one end of a film-spool, and a friction-plate for receiving the opposite end of the spool and being pivotally mounted in the case to swing in the plane of its frictional 75 bearing-face.

3. The combination with a roll-holder case, 80 of a fixed spool-receiving trunnion mounted within the case, a fixed post parallel with the trunnion, a sleeve mounted to slide and rotate upon the post, a friction-plate carried by the sleeve for coöperating with the fixed trunnion to hold the spool, and a spring for forcing the plate toward the trunnion.

4. The combination with a roll-holder case, 85 of a fixed spool-receiving trunnion within the case, a swinging friction-plate for engaging the opposite end of the spool, and being adapted to slide longitudinally upon its pivot, and a spring for forcing the plate toward the 90 fixed trunnion.

5. The combination with a roll-holder case, 95 of a rod within the case, a sleeve mounted upon and in sliding engagement therewith, a friction-plate for carrying a film-spool and 100 having a stud upon which the spool may rotate, such plate being capable of an oscillating movement about the rod, a stem projecting radially from the sleeve, a guide-plate for such stem and having a lateral recess, a spring 100 acting upon the sleeve in opposition to the guide-plate, and a trunnion mounted within the case for coöperating with the friction-plate to hold the spool.

6. In a roll-holder, the combination with a 105 case, of a pair of oscillating plates for supporting the film-spoons, a fixed trunnion for receiving the upper end of the delivering-spool, a rotatable trunnion for engaging and interlocking with the receiving-spool, and being controllable from without the case, and springs for forcing the oscillating plates upwardly. 110

7. In a roll-holder, the combination with a 115 case, of a pair of posts set across the interior 120 of the case, a sleeve mounted loosely upon each post, a supporting-plate projecting radially from each sleeve and adapted to rotatably carry a film-spool, a stem projecting from each plate, a fixed guide-plate for each stem, 120 and having a lateral recess, studs mounted within the case to coöperate with the supporting-plates for carrying the spools, and springs forcing the plates toward the studs.

JOHN A. MOSHER.
